United States Patent Office.

FREDERICK ORTLIEB, OF WILLIAMSBURG, NEW YORK.

Letters Patent No. 68,382, dated September 3, 1867.

IMPROVEMENT IN CONDENSERS.

The Schedule referred to in these Letters Patent and making part of the same.

TO WHOM IT MAY CONCERN:

Be it known that I, FREDERICK ORTLIEB, of Williamsburg, in the county of Kings, and State of New York, have invented a certain new and improved Air and Gas-Exhausting Attachment to Steam-Engine and other Condensers, of which the following is a full, clear, and exact description, reference being had to the accompanying drawing, forming part of this specification, and in which—

Figure 1 represents a vertical section of an apparatus constructed according to my improvement.

Figure 2 a plan of the same, and

Figure 3 an outside elevation of said apparatus connected, as illustrated by red lines, with a surface condenser and its pertaining devices.

Like letters indicate parts throughout the several figures.

The object of my invention, which is more particularly designed to work in connection with a surface condenser, is to dispense with the use of an air-pump for extracting the air and gases from the chamber or spaces into which the steam to be condensed passes, and, in thus dispensing with an air-pump, to avoid not only the cost of such device and its maintenance in working order, but the liability to derangement and failure incidental to all such contrivances, and to economize and reduce that consumption of fuel and expense which the working of an air-pump, to clear the condenser, invariably entails.

Having thus specified the object sought to be attained, the nature of my invention consists in a combination with the outboard delivery of the condenser, through which the water used to condense the steam is circulated, of a novel arrangement of siphonic pipe or tube operating to produce a Torricellian vacuum, and inner pipe for extraction of the heated air and gases from the steam-condensing spaces or chamber of the condenser. And said invention further consists, in such a combination, in giving to the pipe which is used for extracting the heated air and gases from the steam-condensing spaces or chamber of the condenser, an adjustable character for operation, in connection with a tapering construction of the outer siphonic pipe or tube, to control or regulate the outflow of water through the latter.

Referring to the accompanying drawing, A represents the outboard delivery of the condenser, which I make of reservoir form, and, when practicable, arrange at about thirty-three (33) feet above the level of its outflow, that may here be supposed to be into a river or stream, B, with which the communication is established by a pipe, C, of tapering or contracted form, at or near its bottom, as shown at b. This pipe C is in constant communication, through its outboard delivery-chamber A, with the condenser, and a continuous circulation or passage of water kept up between or through it and the several tubes or water-spaces of the condenser by a rotary or other circulating pump, drawing water from below and discharging into the condenser above. When water under pressure is otherwise obtainable, of course the pump may be dispensed with, but in case of using a circulating pump I prefer to make at least one of the injection deliveries from said pump furnish a head or pressure more or less above the level of the condenser for the purpose of more perfectly filling the water-spaces of the condenser to the exclusion of air, but such altitude of the injection water need add but little to the labor of working the circulating pump, as a siphonic action or counterbalance is established to or of the main lift by the action of the descending column in the pipe C, which, exhausting the air in the condenser, operates as a vacuum on the column being raised by the pump. In this way the water may be said to circulate *in vacuo* through the condenser. Connected with the condenser at its top, in free communication with the steam-condensing space or spaces thereof, is a pipe, D, of suitable diameter for extraction of the air and gases, the water formed by condensation of the steam being separately drawn off by a lower pipe through a feed-pump and returned to the boiler. The pipe D, which is represented as of bent or angular form, is arranged, by a suitable connection or extension, to pass through the outboard delivery-chamber A, said connection or extension D' being further passed downwards within the pipe C, which forms a surrounding jacket to it, having an intervening annular space. The pipe D is made a fixture, and may be supported or held by a pillar, E, or otherwise, but the extension branch D' of said pipe is vertically adjustable to regulate the position of its lower end within the cone b of the siphon pipe C. This adjustment may be effected by a screw formation, e, of the extension pipe D' at its junction with the pipe D that fits through a stuffing-box, d, therein, and it may be through a guide, f, to steady the vertical movement of the extension pipe, which may further be steadied by a guide, g, below. F is a revolving screw-box or wheel, working in fixed bearings in a frame, G, and receiv-

ing through it the screw formation *c* of the extension pipe *D'*, so that by turning said screw-box to the right or left the extension pipe is raised or lowered, as circumstances may require.

On starting the apparatus the extension pipe *D'* is lowered by turning the screw-box *F* so as to close or nearly close the conical outlet *b* after the manner of a valve, when the circulating pump is set in motion to fill the water-space or chambers of the condenser, outboard delivery-chamber *A*, and siphon pipe *C*, till an overflow is established from the condenser through a weighted or other valve provided for the purpose. This insures all air being discharged from the water space of the condenser, so that the after-circulation is kept up *in vacuo*, as it were. The extension pipe *D'* is then raised to establish a flow through the cone *b*, and the overflow-valve of the condenser closed, when, by a circulation of water being established by the pump through the water-tubes and pipes or spaces of the condenser, outboard delivery *A*, and down through the siphon pipe *C*, the water descending in the latter draws upon the condenser to establish an equilibrium with the lift or approximation thereto, or to suck upon the condenser, as it were, and at the same time to draw off air and gases by the pipe *D* and its extension *D'*, entering, in the working of the engine or otherwise, the steam-condensing space or spaces of the condenser, and discharging it with the outflow through the cone *b* into and through the stream or water in which the lower end of the siphon pipe *C* is placed. By this means a more or less perfect vacuum is established through the pipe *D* and its extension *D'* in the condenser, and the same maintained without the aid of an air-pump. The outflow through the pipe *C* may be regulated to suit requirements by simply raising or lowering the extension pipe *D'* so as to more or less contract the outlet through the cone *b*, increasing, for instance, the discharge of water in summer; when the atmospheric temperature is high, and diminishing it in winter, when the temperature is lower, and a less rapid circulation of water through the condenser necessary. In some cases this adjustability or valvular action of the extension pipe *D'* may be dispensed with and a fixed outflow through the pipe *C* be established.

What I claim as my invention, and desire to secure by Letters Patent, is—

1. The outer siphonic pipe through which the water from the condenser flows for extracting the air and gases from the steam-condensing spaces through a pipe or pipes communicating therewith, essentially as set forth.
2. The combination of the water-circulating or siphonic pipe *C* with the pipe *D* or its extension *D'*, made adjustable so as to regulate the outflow through the pipe *C*, for operation in connection with the condenser, substantially as specified.

FRIDR. ORTLIEB.
